COOLER

Adam Stutz, Chicago, Ill.

Application August 10, 1933, Serial No. 684,544

1 Claim. (Cl. 225—21)

The invention relates to improvements in coolers adapted for liquid beverages.

The main object of the invention is to provide a novel cooler to insure the effective cooling of 5 beverages for a considerable period.

Another object of the invention is to provide a cooler in which a uniform pressure can be maintained, by means of which any amount of the beverage can be drawn from within.

10 A further object of the invention is to provide a cooler of economical size, which can be easily transported from place to place.

A still further object of the invention is to provide a cooler, which will be compact, simple, 15 easily assembled and efficient in carrying out the purpose for which it is designed.

With the foregoing and other objects in view, which will appear as the description proceeds, the invention consists in certain novel features 20 of construction, arrangement and combination of parts, hereinafter more fully described, illustrated in the accompanying drawing and particularly pointed out in the appended claim.

It is to be understood that various changes 25 in the form, proportion, size and minor details of the structure may be made without departing from the spirit, or sacrificing any of the advantages of the invention.

For the purpose of facilitating an understanding 30 of my invention, I have illustrated in the accompanying drawing a preferred embodiment thereof, from an inspection of which, when considered in connection with the following description, my invention, its mode of operation, assembly 35 and many of its advantages should be readily understood and appreciated.

Referring to the drawing, in which similar characters of reference are employed to indicate corresponding or similar parts throughout the 40 several figures in the drawing:

Figure 1 is a fragmentary enlarged vertical section of the cooler on line 1—1 of Figure 2.

Figure 2 is a fragmentary elevational view of 45 the cooler.

Figure 3 is a top view of the cooler.

The cooler 1, is comprised of a cylindrical shell 2, a bottom part 3, and a top part 4. The bottom part 3, and the top part 4, are secured to the cylindrical shell 2, by means of the double seams 50 5, and 6, respectively.

The container is supported by the ring 8, secured to the bottom part 3, and by the neck portion 9, of the top part 4.

The space 10, between the cooler 1, and the 55 container 7, is filled with the cork 11.

The gasket 12, fits within the interior 13, of the container 7, and is supported on the top portion 14, of the container 7, by means of its horizontal flange 15.

The cap 16, retains gasket 12, in its place by 5 means of its lower projections 17, and 18, respectively. The cap 16, has a recess 19, at its top and a hub 20, within its interior, with a recess 21, and a hole 22, at its center.

The valve 23, is comprised of a ball 24, a stem 10 25, with a portion of reduced diameter 59, and a threaded projection 26, secured within the knob 27. The knob 27, has a recess 29, which houses the spring 30.

The knob 27, slidingly fits in the recess 19, at 15 the top of the cap 16, by means of its projection 28.

The knob 27, has a recess 29, which houses the spring 30.

The recess 21, has a threaded portion 32, to 20 receive the threaded portion 61, of the delivery pipe 33, secured by the nut 34.

The cap 16, has a covered passageway 35, which has a threaded portion 36, to receive the threaded portion 62, of the flow pipe 38, secured by the nut 25 39.

The air-intake 40, is a hollow tube closed at its far end 41. It has a threaded portion 42, by means of which it is secured within the cap 16, and retained by the nut 43. The orifice 44, permits 30 the flow of air within the interior of the container 7, when the end 60, is connected to the air supply.

The safety valve 45, permits the escape of air of excessive pressure, thereby, insuring a uniform 35 pressure within the container.

The bail 46, is retained in the brackets 47, secured to the top part 4, of the cooler 1. The bail 46, supports a grip 48, at its top portion.

The clamp 49, is pivotally mounted to the top 40 4, by means of the bracket 50, secured to the top part 4. The clamp 49, retains airtight the removable cap 16, on the cooler 11, by the slot 51, formed at the middle portion of its free end, sliding over a pivotally mounted screw 52, housed in 45 the bracket 53, secured to the top 4, and is retained in its place by the wing nut 54.

The clamp 49, has a hole 55, at the center of its top, to permit the free travel of the knob 27, when the beverage is drawn from the container 7. 50

The bracket 56, retains the flow pipe 37, in its place and is secured to top part 4.

To fill the container 7, with the beverage, the clamp 49, is raised in the position 57, by loosening the wing nut 54, on the screw 52. The cap 16, 55

is then removed and the container 7, is filled. When the filling is done, the cap 16, is replaced and the clamp 49, is brought down to its former position.

- 5 To draw the beverage from the container 7, the free end 60, of the air-intake 40, is connected with the air supply. When the uniform pressure is established within the container by pressing the knob 27, downward, the ball 24, leaves its seat 31.
- 10 The beverage rises within pipe 33, fills the passage 58, around the stem 59, flows through the passage-way 35, and flow pipe 38, to an outside container.
- 15 I claim:

- 15 A cooler comprising a shell and a container

separated by insulating material, a removable cap having an inserted hollow tube with a closed end and an orifice to convey compressed air into said container, a dispensing valve located in the cap and having a stem of various diameters, the 5 larger one of which fits snugly into a hub of the cap, said stem having a spring supported knob at the top of the cap, a pipe supported by said cap and projecting close to the bottom of said container, a discharge spout secured to the cap and 10 communicating with the pipe through a channel in the cap, said valve being located in the channel between the spout and the pipe.

15 ADAM STUTZ. 15
